FRANÇOIS LACAMBRA, OF BAYONNE, FRANCE.

SPRING-LINK.

1,216,463.

Specification of Letters Patent.

Patented Feb. 20, 1917.

Application filed August 8, 1916. Serial No. 113,783.

To all whom it may concern:

Be it known that I, FRANÇOIS LACAMBRA, a citizen of the French Republic, residing at 1 Rue Poissonnerie, Bayonne, France, have 5 invented certain new and useful Improvements in Spring-Links, of which the following is a specification.

This invention relates to spring links or shock absorbers of the kind in which two 10 rods, bars or stems around which a spring is coiled are provided at opposite ends with eyes and with flanges or collars which permit the two rods or the like to be placed close together side by side in which position 15 they are held by the spring which is compressed by the flanges when tension is applied to the ends of the link.

This invention has for its object to provide an improved metal spring link or bar 20 of this type which can be applied to various industries, particularly to gymnastic or exercising apparatus, to buckle-making, to the stoppers of flasks and bottles containing beverages or liquids which are sterilized or 25 under pressure, to the bung-holes of casks and other uses and is mainly distinguished from known devices by the employment of rods of circular section suitably flattened along their contacting surfaces, the employ- 30 ment of fixed collars or flanges which are notched instead of slotted for the passage of the rods, and the forming of the eyes by bending the ends of the rods as hereinafter described.

35 It may here be pointed out that the application of spring links of other types than those herein described to bottle stoppers and buckles is not claimed as such have been already employed.

40 In a practical form, the link or connection comprises two metal rods or bars of half round section or formed with a flat face over the whole length thereof so that these rods can bear and slide one against the other 45 with their flat surfaces in contact. One of the ends of each rod is provided with a collar in which a rectangular or trapezoidal notch is cut for the accommodation of the other rod and the other end is bent over to 50 form an eye the bending being effected in such manner that the eye serves as a stop.

The two rods are juxtaposed with the eyes at the outer ends.

55 A helical spring is coiled around the two juxtaposed rods and lies between the collars of the two rods. The length of the spring

and the number of its convolutions may vary.

The accompanying drawing illustrates this device and some of its applications, on 60 the one hand to a buckle and on the other hand to the lever stoppers of bottles, flasks or other receptacles.

Figure 1 is a side elevation of the spring link.

Figs. 2, 3 and 4 are transverse sections of the link taken respectively through $x-x$, 65 $z-z$ and $y-y$.

Fig. 5 is a side elevation of a spring link in which each of the plates which are on 70 one of the ends of each of the two rods belonging to the link is connected with a graduated scale placed parallel to the axis of the said rods.

Fig. 6 is a transverse section of this form 75 of the link taken through $x'-x'$.

Fig. 7 is a view as seen from the right extremity.

Fig. 8 a front elevation of a gymnastic apparatus for use by hand, comprising the 80 employment of two links.

Fig. 9 shows the method of connecting the two sliding rods which join the handles of this gymnastic hand apparatus.

Fig. 10 is a longitudinal section of a cask 85 bung-hole furnished with a plug held opposite the body of the bung-hole by two links placed outside near the side of the plug.

Figs. 11 and 12 are respectively a side view and a plan of an ordinary buckle A 90 made extensible by the application of two spring links.

Fig. 13 illustrates known forms of bottle necks D or flasks B in which the stopper A' is firmly secured to the mouth by the application of two spring links coöperating with 95 the ordinary links employed on these receptacles.

As shown the spring link (Figs. 1 to 4) consists of two rectilineal metal rods 1 of 100 circular or other section but each having a flat face 2 by means of which they rest one on the other and can freely slide one against the other. Each rod 1 is furnished at one of its ends with a collar or flange 3 notched 105 at 4 to enable the flat surfaces of the rods to lie close together. The notches 4 correspond in shape to the sections of the rods to enable them to slide freely in the notches. The outer opposite ends of the rods 1 are 110 bent to form eyes 6. When the two rods 1 are superposed, their flat parts 3 and their

eyes 6 are placed opposite one another and the eye part of one of the rods comes against the outer unnotched surface of the flange 3 of the other rod. A spiral spring 5 incloses the two juxtaposed rods and its coils which are not compressed and the number of which is variable extend over its whole length between the flanges 3. In order to mount the spring 5 around the rods 1, the latter before being bent to form the eyes 6, are passed in opposite directions into the hollow center of the spring; the eye 6 is then formed at the end of each rod facing the flange 3 of the other rod, the end 15 of the eye being placed against the unnotched portion of the flange 3.

In the form of the link shown in Figs. 5 and 7, one of the plates 3 forms part with a scale 7 which is placed parallel to and at a slight distance from the juxtaposed rods 1, the other plate 3' is furnished with an arm 8 formed by a wire, into the loop or buckle 9 of which the end of the scale 7 enters. On this scale starting from the 25 loop or buckle 9 a runner 10 is threaded and following this an india rubber ring 11. If a pull toward the outside be exercised on the hooks 6 of the link the plates 3, 3' come together compressing between them the 30 spiral spring 5, the arm 8 then causes the runner 10 and the ring 11 to slide on the scale 7. When the pull ceases the arm 8 moves toward its initial position, the runner 10 remains in its place on the scale and shows on this scale the degree corresponding to the maximum of the force applied.

One or more spring links may be applied to numerous objects so as to make them extensible.

40 In the gymnastic apparatus for use by hand illustrated in Figs. 8 and 9, the two parallel handles H made of wood or other material have each running through them longitudinally a metal rod 15 which extends 45 to the outside and takes a position perpendicular to the handle, its end is "counter" bent at 16 at a right angle toward the outside, that is to say parallel to the handle, here it receives a ring 17. Into each of the 50 two rings 17 situated on the same side of the apparatus runs one of the two hooks 6 of the same link E. The parts of the rods 15 which come parallel and laterally to the handles H have a smooth part along which 55 they lie and slide one against the other. In order to reduce the friction, a roller 19 running on the smooth part of the adjacent rod 15 may be pivoted in each rod 15, being retained opposite the other rod 15 by a ring 60 20 furnished with a roller 21 running over the outer surface of this other rod.

In the cask bung-hole Fig. 10 the plug C rests on the body B; two links E are fixed by their hooks 6 on rings 22 implanted in 65 the body B and on open hooks 23 fixed in

the plug C. When over-pressure arises in the cask provided with this bung-hole the plug C is raised, the springs 5 of the links E are compressed between the plates 3 and the gas is able to escape into the atmosphere. Directly the over-pressure ceases the expansion of the springs 5 brings the plug C on to the body B. The hooks 23 being open, the links E may be easily released from the plug C, which, being freed, allows of the 75 cask being filled or emptied.

In Figs. 11 and 12 two spring links E of the type mentioned above are attached by one of their eyes to the cross bar a of a buckle A. In the arrangement shown in the upper part of Fig. 12 a notch b is formed in the cross bar a for positioning the eye 6. In the arrangement shown in the lower part a projection b' is formed on the cross bar a for retaining the eye 6 in position. The opposite eyes 6 of the two spring devices are held parallel and connected with the end eyes d of a coupling rod e placed parallel to the cross bar a of the buckle A.

In Fig. 13 two spring links E are combined with the metal mountings applied to bottles or receptacles B with the view of firmly fixing the stopper A' in order to insure the tight closing of the mouth of the bottle. These spring links facilitate the release of the said stopper, avoiding a too great compression of the ring o made of india-rubber or other material.

The stopper A' has running through it in the usual manner a wire e but the ends of this wire instead of hooking into the eyes f of the link g are pivoted in the opposite holes h in the neck of the bottle. A spring link E of the type mentioned above is secured by one of its eyes 6 to the arm e' 105 which is flattened and perforated. The other link 6 of the spring device is attached to the wire that forms the link g opposite the link f.

What I claim and desire to secure by Letters Patent is:—

1. In a spring link formed by two parallel metal rods surrounded by a spiral spring, the combination of two juxtaposed rectilineal cylindrical rods each having throughout its length a flat surface against which they bear and over which they slide one against the other; of a circular plate fixed eccentrically and invariably to one of the ends of each of the said rods and having a notch extending from the flat surface of the rod on which it is fixed up to the extreme edge of the said plate, the said notch having in section the form of the other rod which is intended to slide freely through it; of a hook formed at the end of said rod, opposite that furnished with a notched plate causing the rod to fold toward its flat surface so that the point of the hook comes opposite the non-notched part of the plate of the other

rod when the rods are superposed and of a spiral spring which comes concentrically to the two superposed rods and very near to their curvilinear periphery the coils or windings of which extend over the whole distance existing between the plates which are at the one end of each of the two rods.

2. In a spring link formed by two parallel metal rods surrounded by a spiral spring, 10 the combination of two juxtaposed rectilinear cylindrical rods each having throughout its length a flat surface along against which they bear and over which they slide one against the other; of a plate, formed 15 with a notch fixed eccentrically to one of the ends of one of the said rods and having opposite the said notch, in which the other rod is lodged and slides, an extension which is provided with a scale extending parallel 20 to the said rod throughout its length; a rod in which a hole is drilled through which the said scale freely runs; of a scale extending parallel to and at a slight distance from

the juxtaposed rods and receiving, starting from the arm in which it slides an india-rubber ring and a runner capable of sliding freely on the said scale opposite the graduations thereof; of a hook formed at the end of each rod, opposite that furnished with a notched plate causing the rod to fold toward its flattened surface so that the point of the hook comes opposite the non-notched part of the other rod when the rods are superposed; and of a spiral spring which comes concentrically to the two superposed 35 rods and very near to their curvilinear periphery, the coils or windings of which extend over the whole distance existing between the plates which are at the one end of each of the two rods.

In testimony whereof I affix my signature in presence of two witnesses.

FRANÇOIS LACAMBRA.
